GRINDING MACHINE

Charles Herfurth, Cincinnati, Ohio, assignor to
Cincinnati Grinders Incorporated, Cincinnati,
Ohio, a corporation of Ohio

Application February 29, 1932, Serial No. 595,709

4 Claims. (Cl. 51—166)

This invention relates to improvements in machine tools and especially to improvements in grinding machines.

As is well known, a grinding machine operates most efficiently when its operative surface is traveling at a definite speed, for example, six thousand peripheral feet a minute. Therefore, a cylindrical or disk type grinding wheel is rotated at a speed for causing the wheel's surface to travel at this speed and most machines are designed to rotate the maximum size wheel at this speed when they are new. Frequently no means are provided for increasing the speed of the wheel after it becomes reduced in diameter due to wear or trimming or truing away so that the wheel's surface instead of traveling at the recognized efficient rate of speed is actually traveling at a slower rate of speed, causing the same to wear away at a rapid rate and increasing the cost of the products being ground thereby.

It is, therefore, one of the principal objects of the present invention to provide means for automatically increasing the speed of the wheel as it is worn down.

Another object of the invention is the provision of simple means for effecting this increase of speed.

A further object of the invention is the provision of a self-contained grinding wheel unit for use with grinding machines and including its individual prime mover or motor that is automatically speeded up as the wheel is worn beyond a definite point.

Other objects and advantages of the present invention should be readily apparent by reference to the following specification considered in conjunction with the accompanying drawings forming a part thereof and it is to be understood that any modifications may be made in the exact structural details there shown and described within the scope of the appended claims without departing from or exceeding the spirit of the invention.

In the drawings:

Figure 1 is an elevational view of a grinding machine embodying the improvements of this invention.

Figure 2 is a top plan view of the machine shown in Figure 1.

Figure 3 is an elevational view as seen from line 3—3 on Figure 2.

Figure 4 is a sectional view taken on line 4—4 of Figure 3.

Figure 5 is a sectional view taken on line 5—5 of Figure 3.

Figure 6 is a sectional view taken on line 6—6 of Figure 3.

Figure 7 is a diagrammatic view illustrating the electrical circuit involved in this invention.

Figure 8 is a diagrammatic view illustrating a modification of the invention.

Throughout the several views of the drawings similar reference characters are employed to denote the same or similar parts.

A machine embodying this invention may comprise a bed 10 having formed on the upper surface thereof guideways for guiding a translatable table 11 during its movement relative to the bed 10. Mounted on the table are the usual head stock 12 and tail stock 13 respectively supporting centers 14 and 15 between which the work is mounted for movement with the table. Any desirable means may be provided for effecting the translation of the table, for example, the hand wheel 16 which is operatively connected therewith in the usual or desirable manner.

The bed has secured thereto and projecting from the rear thereof an extension 17 disposed transversely to the direction in which the work table 11 travels and has formed thereon ways 18 and 19 for the grinding wheel carriage 20 movable relatively to the extension 17 toward and from the work supporting table. The carriage 20 has journaled therein a spindle 21 to one end of which is secured a grinding wheel 22 for rotation therewith. A motor 23 being provided and having extending therefrom a shaft 24 to which is secured a pulley or sheave 25 in alignment with a similar pulley or sheave 26 secured to the spindle 21. A belt or other flexible transmission means such as the V-shaped belts 27 being provided for connecting the pulleys 25 and 26 and for transmitting motion from the shaft 24 to the spindle 21.

The motor 23 is adapted to be rotated at a speed for rotating the spindle 21 at the necessary speed to actuate the operative face 28 of the grinding wheel, when the wheel is the maximum size usable in the machine, at the efficient speed of approximately six thousand peripheral feet a minute. This speed is the recommended speed of wheel manufacturers today and it may be increased or decreased depending on the particular type of wheel being used. The sole requirement as far as this application is concerned being that the peripheral speed of the surface 28 be at the recognized most efficient speed.

As is well known, a generous supply of coolant must be supplied to the grinding wheel and work at the point where they engage one an-

other during grinding to prevent burning or otherwise damaging the surface of the work being produced. For this purpose, there is provided a pipe or conduit 29 connected at 30 to 5 the usual pressure supply and terminating at 31 in a nozzle for directing the coolant stream to the desired point. The pipe 29 is supported by a bracket 32 having a pivotal connection at 33 with a bracket 34 for adjusting the pipe to 10 ward and from the grinding wheel. The bracket 34 carrying the bracket 32 is adjustably mounted on the rod 35 for movement in a direction transversely of the axis of the grinding wheel. The rod 35 is keyed or otherwise securely mounted 15 in a bracket 36 integral with or secured to a guard 37 that substantially encloses the grinding wheel 22. In order to confine the coolant and insure its proper supply at the point of grinding, the guard 37 closely encircles the 20 wheel 22 and must at all times be positioned in close proximity therewith. Therefore, as the wheel is worn away the guard is shifted toward the rear of the wheel as respects its grinding point in a radial direction relative thereto.

25 The guard 37 has secured to it in any desirable manner, such as by rivets 38, a bar or guide 39. This bar being provided intermediate its ends with a slot 40 through which a clamp bolt 41 passes for securing same to the carriage 20. 30 The guard is supported by means of anti-friction rollers 42 and 43 each carried by a pad 44 formed on the side of the carriage adjacent the guard by means of pins 45 extending therethrough into the said pad 44. The under surface 46 of the bar 39 rests on the said rollers and rides therealong as the guard is shifted radially of the wheel.

It is well known that the speed of certain motors is increased by inserting resistance in series with the field circuit, which is especially true of a direct current shunt wound motor. Therefore, if the resistance is shunted the speed of the motor is reduced and may be considered the normal speed thereof. As shown in Figure 7, the 40 main electric lines or leads 47 and 48 have wired between them the prime mover or motor 23, the field of which includes the conduits 49 and 50 having between them the field coil 51 and a resistance 52 between the conduit 50 and motor 23. By reference to this figure, it will be noted 45 that the conduit 50 is shunted around a resistance 53 and has electrically connected thereto in a switch 54 held normally in a closed position by means of a spring 55. From the foregoing it will be noted that if the switch 54 is opened the circuit through the conduit 50 will be broken and must pass through the resistance 53 thereby increasing the speed of the motor 23. Any suitable or desirable means may be 50 provided for opening this switch 54, which should take place at a definite point in the wear of the grinding wheel or when its diameter is reduced to such a point that the speed thereof decreases the peripheral speed of the operative 55 face of the wheel beyond the efficient grinding point. As shown in the drawings, the guard bar 39 is provided on its extreme rear end with a cam block 56 having formed thereon the cam face 57 for engagement with a roller 58 carried 60 on the end of an arm 59. This arm 59 is pivoted at 60 which extends through a plate 61 secured to the side of the carriage 20. Secured to the plate 61 and projecting interiorly of the carriage 20 is a switch mechanism 62 carrying 65 the usual or desirable parts for operating the

switch 54 to break the electrical circuit. As shown in Figure 7, this mechanism may comprise a cam 63 on the end of the pivot stud 60 and operable therewith for opening the switch against the resistance of the spring 55.

5 The operation of the device is as follows. A full size wheel, shown in full lines in Figure 3, is mounted on the grinding wheel spindle 21. The guard 37 is adjusted to the position, again shown in full lines in Figure 3, at which time 10 the parts are in proper relation for confining the coolant spray to the machine and insuring the proper quantity of coolant being delivered to the point of contact between the wheel and work where the actual grinding takes place. 15 As the wheel is worn and trimmed away during practice the operative face 28 recedes necessitating the adjustment of the guard 37 radially of the wheel and toward the left, as seen in Figure 3. The surface 28 of the wheel eventually 20 reaches the dot and dash line 64 of Figure 3, which represents substantially the size of the wheel when half worn away. As the guard 37 is adjusted radially of the wheel during this 25 wearing away, as above described, the cam block 56 is gradually approaching the roller 58 and when the wheel reaches its mid useful position the guard and parts carried thereby are in the 30 position shown in dotted lines in Figure 3, thereby actuating the arm 59 and opening the switch 54, cutting in to the electrical circuit the resistance 53 and speeding up the rotation of the 35 motor 23. The new speed of the motor is such that the peripheral face of the grinding wheel, as represented by the broken line 64, will be increased an amount to bring its peripheral travel 40 up to the speed of the operative surface 28 so that the grinding wheel will effect the desired stock removal at the recognized efficient rate.

45 The modification shown in Figure 8 illustrates a plurality of resistances 53a, 53b and 53c between the motor field 51a and the motor. Each of these resistances is shunted by a conduit 50a, 50b and 50c so that the motor 23 is rotated at its normal speed as when a new full sized wheel 45 is being used as above described. However, instead of stepping up the motor speed once during the life of the wheel it may be stepped up a plurality of times such as after each inch of 50 wear of the wheel. For this reason each of the 55 shunt lines or leads 50a, 50b and 50c are provided with a switch such as 54 and indicated by the reference numerals 54a, 54b and 54c respectively held closed by springs 55a, 55b and 55c. These switches are adapted to be opened by cams 55a, 55b and 55c each being similar to the cam 63a, 63b and 63c each being carried by an arm similar to the arm 59. Therefore, instead of a single 60 switch being carried by the carriage 20 a plurality of them is mounted thereon and each is successively actuated during the rearward adjustment of the guard 37 and thereby at all 65 times keeping the surface of the grinding wheel traveling at its proper efficient speed.

65 What is claimed is:

1. In a grinding machine of the class described the combination of a bed, a grinding wheel carriage carried thereby, a spindle journaled in the carriage, a grinding wheel secured to the spindle, a prime mover operatively connected with the 70 spindle for rotating same and the grinding wheel secured thereto, said spindle and wheel being rotated at a rate to cause the operative face of the wheel to have a peripheral speed for effecting efficient stock removal from a work piece, said wheel 75

- being reduced in diameter due to wear and truing thereof and thereby reducing the peripheral travel of the wheel to a point below its efficient stock removal point, and means for increasing the rate 5 of rotation of the prime mover and rate of rotation of the spindle and grinding wheel for increasing the peripheral speed of the worn wheel to the point of initial peripheral travel, said means including an electrical resistance adapted to be 10 inserted in the electrical circuit of the motor, a switch for connecting the resistance in the circuit, a guard enclosing the wheel and adjustable relative thereto as the wheel is worn away, a bar secured to the guard, means associated with the 15 bar for securing the guard to the carriage in adjusted positions relative to the wheel, and a cam mounted on the bar for closing the switch when the guard reaches a definite position in its range of adjustment representative of a worn or reduced 20 wheel.
2. In a grinding machine of the class described the combination of a bed, a grinding wheel carriage carried thereby, a spindle journaled in the carriage, a grinding wheel secured to the spindle, 25 a prime mover operatively connected with the spindle for rotating same and the grinding wheel secured thereto, said spindle and wheel being rotated at a rate to cause the operative face of the wheel to have a peripheral speed for effecting 30 efficient stock removal from a work piece, said wheel being reduced in diameter due to wear and truing thereof and thereby reducing the peripheral travel of the wheel to a point below its efficient stock removal point, and means for increasing 35 the rate of rotation of the prime mover and rate of rotation of the spindle and grinding wheel for increasing the peripheral speed of the worn wheel to the point of initial peripheral travel, said means including an electrical resistance adapted to be 40 inserted in the electrical circuit of the motor, a switch for connecting the resistance in the circuit, a guard enclosing the wheel and adjustable relative thereto as the wheel is worn away, a bar secured to the guard, means associated with the 45 bar for securing the guard to the carriage in adjusted positions relative to the wheel, a cam mounted on the bar for closing the switch when the guard reaches a definite position in its range of adjustment representative of a worn or reduced 50 wheel, and anti-friction means for permitting ready adjustment of the guard.
3. In a grinding machine of the class described the combination of a bed, a grinding wheel carriage mounted thereon for transverse movement relative thereto, a grinding wheel spindle journaled in the carriage, a grinding wheel secured to the spindle, a prime mover belted to the spindle for effecting its rotation and the grinding wheel secured thereto, said motor effecting the rotation of the grinding wheel, when full size, at its most efficient peripheral speed, the peripheral speed of the wheel being reduced as the wheel is worn and trued away, a guard mounted on the carriage for adjustment relative thereto to closely engage the wheel to confine the coolant usual with grinding wheels, and means carried by the carriage for movement therewith and operable upon movement of the guard for increasing the peripheral speed of the worn and reduced wheel to its initial peripheral speed, said means including a resistance in the prime mover circuit, a switch on the carriage normally shunting the resistance, a bar on the guard for movement therewith as it is adjusted relative to the carriage and wheel, and cam means on said bar for actuating the switch. 10 15 20 25 30 35 40 45 50
4. In a grinding machine of the class described the combination of a bed, a grinding wheel carriage mounted thereon for transverse movement relative thereto, a grinding wheel spindle journaled in the carriage, a grinding wheel secured to the spindle, a prime mover belted to the spindle for effecting its rotation and the grinding wheel secured thereto, said motor effecting the rotation of the grinding wheel, when full size, at its most efficient peripheral speed, the peripheral speed of the wheel being reduced as the wheel is worn and trued away, a guard mounted on the carriage for adjustment relative thereto to closely engage the wheel to confine the coolant usual with grinding wheels, and means carried by the carriage for movement therewith and operable upon movement of the guard for increasing the peripheral speed of the worn and reduced wheel to its initial peripheral speed, said means including a resistance in the prime mover circuit, a switch on the carriage normally shunting the resistance, a bar on the guard for movement therewith as it is adjusted relative to the carriage and wheel, cam means on said bar for actuating the switch, and anti-friction means supporting the guard on the carriage to permit ready adjustment of the guard. 20 25 30 35 40 45 50

CHARLES HERFURTH.
